WAX THREAD SEWING MACHINE

Henry Graf, Newburyport, Mass., assignor to
 United Shoe Machinery Corporation, Paterson,
 N. J., a corporation of New Jersey

Application May 23, 1933, Serial No. 672,411

6 Claims. (Cl. 112—42)

The present invention relates to sewing machines of the same general type as described in the U. S. Patent No. 1,108,560 granted August 25, 1914 to Andrew Eppler, employing waxed 5 thread, and more particularly to improvements for preventing the work from being soiled in such machines by contact with the wax carried by the thread.

The machine described in the Eppler patent 10 is provided with main and auxiliary take-ups having heated guide rolls over which the waxed thread passes to the point of operation on the work, so arranged as to permit small particles of melted wax under certain conditions to drop 15 upon the work being sewn. The object of the present invention is, therefore, to shield the work against discoloration and soiling occasioned by such contact with the wax.

A feature of the invention contemplates the 20 provision in a machine of this type of a shield or trough for catching the wax stripped from the thread as it passes the thread guides above the work and causing it to be conducted back to the thread as it travels towards the sewing 25 point in the work.

This and other features of the invention will 30 be clearly understood from an inspection of the accompanying drawing in which, Figure 1 is a view in side elevation of a welt sewing machine embodying the same in its preferred form; Figure 2 is a view in front elevation of a portion of the sewing machine illustrated in Figure 1; Figure 3 is a plan view of the wax trough of the present invention; and Figures 4 and 5 are 35 views in side and rear elevations, respectively, of the wax trough.

The machine illustrated is provided with a curved hook needle 2, a take-up 4, an auxiliary take-up 6, a thread arm 8, a welt guide 10, a 40 looper 12, a back rest 14, and other stitch forming and work supporting devices having the same general arrangement and mode of operation as the corresponding parts of the welt and turn sewing machine disclosed in the patent 45 above referred to.

The thread is supplied to the stitch forming devices from a suitable source, and is guided over guide rolls 16 and 18 carried by the main and auxiliary take-up arms, respectively. The 50 thread is waxed before entering the machine and is maintained in a heated condition until the stitches are formed by heating the parts adjacent the stitch forming mechanism. To heat the rolls 16 and 18, the take-up arms 4 and 6, respectively, are positioned closely to a

substantially flat vertical plate 20 carrying at its forward part a heater 22. Heat is transferred from the heater 22 to the plate and to the arms supporting the rolls 16 and 18 so that the thread passing over them is heated thereby. The rolls 60 being directly over the work as it is held in position in the machine, heretofore have caused wax to be stripped from the thread and to be deposited on the work being operated upon.

To prevent the work from being soiled by contact with the wax stripped from the thread in passing to the stitch forming devices, according to the present invention, a wax trough 24 is disposed beneath the thread guiding rolls 16 and 18 on the take-up arms so as to catch the wax 70 stripped from the thread. The wax trough 24 is removably mounted on the lower part of the heater 22 in a position substantially horizontal but with the inner surface of the trough inclined somewhat downwardly towards the back of the 75 machine. The thread extends from the guide roll 16 through an opening 26 in the wax trough. Wax is prevented from passing through the opening by an upturned flange on the trough about the edges of the opening, and an oblique 80 slot 28 communicates from the outside of the trough with the opening to facilitate threading of the machine. From the guide roll 16 to the looper 12, the thread is substantially straight while the machine is operating and the opening 26 is sufficiently large to clear the thread as the 85 looper moves about the needle. During operation of the machine, the particles of wax stripped from the thread fall into the wax trough 24 and are melted by the heat supplied 90 by the heater 22, causing the wax to run down the incline of the bottom of the wax trough 95

To prevent the trough from filling and overflowing, there is formed at the lowest portion thereof a tubular conductor 30 arranged, when the trough is mounted on the machine, to take a position directly above the looper 12. The looper, being formed, as usual, with a thread passage 32, will receive the liquid wax running 100 through the conductor 30 and reapply it to the thread as it passes therethrough.

The looper, in the normal operation of the machine, acts to lay the thread in the thread finger and then move about the end of the 105 needle in a continuous path. During the greater part of the time in each cycle of the machine, the looper is in approximately the position shown in Figure 1, with the thread passage 32 directly beneath the conductor 30. When the 110

machine is brought to rest, the looper is also in this position. While the looper is threading the needle, the thread passage 32 is moved out from under the end of the conductor 30 and is returned again after the needle is threaded. If a drop of melted wax should happen to collect at the lower end of the conductor 30 while the looper is moving around the end of the needle, the close proximity of the looper and the thread extending from the looper to the guide roll 16 on the take-up as the looper returns to the position of Figure 1, will cause the drop of wax to be precipitated onto the thread.

By this construction, the wax stripped from the thread as it passes the guide rolls 16 and 18 will always be caught and returned to the thread, insuring proper formation of stitches in the work with the wax originally applied to the thread, while at the same time, the work will be kept free of discoloration and other undesirable effects produced by contact with the wax throughout unstitched areas.

What is claimed is:—

1. A wax thread sewing machine having, in combination, a hook needle, a needle threading looper having a passage for the thread, heated guides over which the thread passes to the looper, a trough disposed beneath the heated guides for catching wax which is separated from the thread in passing over the guides, and means for transferring the wax from the trough to the thread as it passes to the work.

2. A wax thread sewing machine having, in combination, a curved hook needle, a needle threading looper having a passage for the thread, a take-up above the looper, a heated guide on the take-up over which the thread passes to the looper, a trough disposed between the looper and the take-up for catching the wax which is separated from the thread in passing over the heated guide, means for melting the wax in the trough, and a conductor connected with the trough for transferring the wax to the thread as it passes to the looper.

3. A wax thread sewing machine having, in combination, a hook needle, a needle threading looper having a passage for the thread, guides over which the thread passes to the looper, a trough disposed beneath the guides for catching wax which is separated from the thread in pass-

ing over the guides, and a conductor connected with the trough having its lower end in close proximity to the path of the thread extending between said guides and the looper in one position of the looper during each cycle of operation of the machine.

4. A wax thread sewing machine having, in combination, a hook needle, a needle threading looper having a passage for the thread, guides over which the thread passes to the looper, a trough disposed beneath the guides for catching wax which is separated from the thread in passing over the guides, and a conductor connected with the trough having its lower end above the looper at a position in which the wax from the trough will fall into the thread passage when the machine is brought to rest.

5. A wax thread sewing machine having, in combination, a curved hook needle, a needle threading looper having a passage for the thread, a take-up above the looper, a heated guide on the take-up over which the thread passes to the looper, a trough disposed between the looper and the take-up for catching the wax which is separated from the thread in passing over the heated guide, means for melting the wax in the trough, and a tubular conductor connected with the trough at one end and arranged with its other end above the thread passage in the looper in one position of the looper during each cycle of operation of the machine.

6. A wax thread sewing machine having, in combination, a curved hook needle, a needle threading looper having a passage for the thread, a take-up above the looper, a plate along the surface of which the take-up operates, a guide on the take-up over which the thread passes to the looper, a heater connected to the plate for heating the take-up guide, a trough mounted on the machine between the looper and the guide on the take-up to be heated by said heater for catching the wax which is separated from the thread in passing over the take-up guide, and a tubular conductor connected at its upper end with the trough and arranged with its lower end above the thread passage in the looper in one position of the looper during each cycle of operation of the machine.
